(57) CLAIM

The ornamental design for a decorative hair brush, as shown and described.

DESCRIPTION

FIG. 1 is a Perspective view of a decorative hair brush showing my new design;

FIG. 2 is a front elevation view thereof;

FIG. 3 is a rear elevation view thereof;

FIG. 4 is a left side view thereof;

FIG. 5 is a right side view thereof;

FIG. 6 is a top plan view thereof; and,

FIG. 7 is a bottom plan view thereof.

Features of the design are the fluted perimeter of the decorative hair brush and the jeweled inserts shown on the front surface thereof.

The broken line disclosure of the article shown is for illustrative purposes only and forms no part of the claimed design.
